WILLIAM E. ALBERTSON, OF JACKSONVILLE, FLORIDA, ASSIGNOR OF ONE-HALF TO
MAXEY D. MOODY, OF JACKSONVILLE, FLORIDA

SAFETY DEVICE FOR GAS ENGINES

Application filed June 16, 1930. Serial No. 461,589.

This invention relates broadly to automatic means for running off liquids from a container at predetermined degrees of temperature and more specifically to safety devices for preventing bursting of radiators of automobile and other engines at freezing temperatures.

An object of the invention is to provide a novel tap, valve or the like constituting a releasing means for the cooling liquid in the radiator, the valve being automatically opened by a thermostat controlled switch when the temperature drops to freezing so that the water is drained from the radiator. A further object of the invention is to provide a releasing means including a spring pressed valve and its housing, there being provided novel leaf springs and a fuse connecting the leaf springs and coacting with the latter in maintaining the valve closed against the tension of its spring, said fuse being blown by closing of the thermostat controlled switch and disconnecting said leaf springs whereby said valve is freed to be opened by its spring.

A still further object of the invention is to provide an automatic releasing device for liquid containers which will be positive in operation, will be inexpensive to manufacture, and will be formed of a few strong, durable and simple parts which will not easily get out of order.

With the above and other objects in view the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification:

Figure 1 is a side elevation of a motor showing the cooling system thereof equipped with my invention,

Fig. 2 is a detail elevation of the motor heat gauge having a fixed switch contact disposed in the path of movement of the ground-

ed indicating needle to close an electric circuit,

Fig. 3 is a cross sectional view on the line 3—3 of Fig. 2,

Fig. 4 is an end elevation showing the valve and fuse,

Fig. 5 is a vertical sectional view taken on the line 5—5 of Fig. 4, and

Fig. 6 is a diagrammatic view showing the electric circuit.

Referring now to the drawings in which like characters of reference designate similar parts in the various views, 10 indicates an internal combustion engine having a water jacket 11 connected by the usual pipes 12 and 13 to the radiator 14. The temperature of the engine is taken from the water in the water jacket by inserting a thermostat 15 therein which is connected by a tube 16 to a temperature indicating gauge or motor meter 17 located on the instrument panel 18 of the automobile. These parts are of the usual standard construction.

In carrying out the invention, I modify the temperature gauge to produce a thermostat controlled electric switch. To this end a fixed insulated switch contact 19, as best shown in Fig. 2, is fixed to the dial 20 of the gauge in the path of movement of the indicating needle 21 which is grounded and forms a movable switch contact. The fixed contact 19 is preferably located at the 32 degree calibration of the instrument so that when the temperature of the water drops to freezing the needle will touch the fixed contact and close an electric circuit.

In the preferred embodiment of the releasing means for the water in the cooling system I provide a valve housing 22 which is provided with a nipple 23 which may be screwed into the emptying orifice of the water circulatory system, as best shown in Fig. 1. The housing is provided with a collar 24 which is provided with wrench faces 25 to facilitate application and removal of the device. The lower end of the housing is open and is normally closed by a flap valve 26 which is provided with a fiber washer 27 to engage the edge of the housing and prevent leakage. The valve is fixed to an angular lever arm 28

which is hinged by a pin 29 to a lug 30 carried by the housing. A helical spring 31 is enclosed within the housing and confined under tension between the valve and the inner wall 5 of the bore of the housing for opening the valve.

A pair of curved leaf springs 32 and 33 are provided, the uppermost leaf spring being secured to a ring 34 of insulating material 10 which is rigidly fixed to the housing, and the lowermost spring being secured in any preferred manner to the free end of the angular lever 28. An insulating blank of material 35 is inserted between the lever and the leaf 15 spring.

Both leaf springs form a support for a wire fuse 36 which is preferably formed of nickel mickrome, and the ends of which are looped around the respective leaf springs and 20 twisted back upon the body of the fuse, as shown at 37 and 38. The fuse is thus yieldably held under tension by the leaf springs so as not to be broken by shocks and jars. The fuse, furthermore, coacts with the leaf springs 25 in holding the valve 26 closed against the tension of its spring 31.

By now referring to Fig. 6, it will be seen that a conductor wire 39 connects the fixed contact 19 of the motor meter with the uppermost leaf spring 32. Another conductor wire 40 connects the storage battery B with the lowermost leaf spring 33. When the temperature of the water in the cooling system drops to freezing the grounded needle touches 30 the fixed contact 32 thereby closing an electric circuit through the wire 39, leaf spring 32, fuse 36, leaf spring 33, and wire 40 to the battery. When the circuit is closed the fuse is 35 blown and disconnects the leaf springs 32 and 33 whereby the valve 26 is released and the spring 31 thereof instantly opens the valve and empties the cooling system.

If desired, I may locate a switch contact 41, see Fig. 6, at the high temperature end of the 40 motor meter scale to be touched by the needle 21 when the water becomes heated to approximately 212 degrees. To this contact may be connected a wire 42 which leads to a fuse 43 located on the instrument panel 18. Another 45 wire 44 connects the fuse with the primary ignition switch 45 which in turn is connected by a wire 46 to the storage battery. A wire 47 may be connected to the distributor 48 of the ignition system and to the fuse 43. Thus 50 when the needle touches the contact 41 of the ignition system will be short circuited and the fuse 43 will be blown so that the engine must stop running until the temperature of the water is restored to normal. Thus damage 55 from overheated bearings will be prevented while the battery will also be safe from discharge.

Having thus described the invention, I claim:

65 1. An automatic device for emptying liq-

uid from a container comprising a thermostat controlled switch, a liquid releasing means normally closing the emptying orifice of said container and tending to move to open position, and a fuse electrically connected in circuit with said switch and operatively connected to said means to normally hold said means closed, said fuse adapted to be blown by closing of said switch to permit actuation of said releasing means. 75

2. An automatic device for emptying liquid from a container comprising a thermostat controlled switch, a liquid releasing means normally closing the emptying orifice of said container and tending to move to open position, a fuse electrically connected in circuit with said switch, and means for yieldably holding said fuse under tension and co-acting with the fuse in holding said releasing means normally closed, said fuse adapted to be blown by closing of said switch to free said fuse holding means and permit the opening of the releasing means. 85

3. An automatic device for emptying liquid from a container comprising a spring 90 pressed valve for closing an outlet in the container, a thermostat controlled switch adapted to be closed at a predetermined temperature of said liquid, and a fuse electrically connected in circuit with said switch and normally holding said valve closed, said fuse adapted to be blown when said switch is closed thereby to release said valve and permit opening thereof. 95

4. An automatic device for emptying liquid from a container comprising a spring 100 pressed valve for closing an outlet in the container, a thermostat controlled switch adapted to be closed at a predetermined temperature of said liquid, a fuse electrically connected in circuit with said switch, and resilient supports for the fuse operatively connected to the valve and coacting with the fuse in normally holding said valve closed, said fuse adapted to be blown when the 105 switch is closed thereby to release said valve and permit opening thereof by said spring. 110

5. An automatic device for emptying liquid from a container comprising a thermostat controlled gauge needle responsive to 115 temperature changes in the liquid and forming a movable switch contact, a stationary switch contact adapted to be touched by said needle to close an electric circuit, a spring pressed valve for closing an outlet in said container, and a fuse in said electric circuit normally holding said valve closed against the tension of its spring and adapted to be blown when said circuit is closed to release said valve. 120

6. An automatic device for emptying liquid from a container comprising a valve housing adapted to be secured to the container and forming an outlet therefor, a valve hinged to said housing, a spring in the hous- 125

ing for opening the valve, a pair of leaf springs one of which is connected to the housing and the other to the valve, a fuse connecting said leaf springs and coacting therewith to normally hold said valve closed against the tension of its spring, and a thermostat controlled switch adapted to be closed at a predetermined temperature of said liquid and electrically connected in circuit with said fuse, closing of the switch adapted to blow said fuse and disconnect said leaf springs whereupon said valve is opened by its spring.

7. A device for preventing bursting of automobile radiators at freezing temperatures comprising a valve housing adapted to be connected to the water circulatory system of the motor, a spring pressed valve normally closing the outlet of said housing, a thermostat controlled switch adapted to be closed by a predetermined variation in temperature in said system, and a fuse electrically connected in circuit with said switch and normally holding said valve closed against the tension of its spring, said fuse adapted to be blown by closing of said switch to permit said valve to be opened by its spring.

In testimony whereof I affix my signature.
